WARP PRINTING MACHINE

Theodore H. Rush, Bloomsburg, Pa., assignor to
 The Magee Carpet Company, Bloomsburg, Pa.,
 a corporation of Pennsylvania

Application April 18, 1933, Serial No. 666,763

13 Claims. (Cl. 91—12.01)

This invention relates to warp printing machines of the type commonly used in the printing of pile warps for tapestry carpets and similar textile products.

5 Machines of the type noted usually employ a drum of relatively large diameter, commonly referred to in the trade as "tap drum". The warps to be printed are wound in continuous spiral form on the peripheral surface of the tap drum, in 10 substantially lateral abutting relation to each other to form a single layer on the face of the drum, for receiving coloring matter from an applicator consisting of a roll or wheel rotatably mounted in a carriage operable transversely of 15 the drum and provided with a color pan arranged to supply the coloring matter to the printing element.

The color carriage and applicator are adapted to be moved across the face of the tap drum while 20 the same is at rest, between intermittent rotations of the drum by which various portions, lengthwise of the warps, are brought into printing position in line with the path of transverse movement of the carriage.

25 The circumference of the tap drum heretofore has been substantially equal to a length of a pile warp necessary to produce pile tufts in a single warpwise line throughout substantially one-half of the length of a large size rug, for example, a 30 9 x 12 rug, which necessitated the printing of another warp thread of equal length in reverse order to the first said length, to provide for the pile tufts in the second half of the rug, in cases where the pattern at each end of the rug are exact duplicates.

35 Such double printing necessitated the use of two warp beams in the loom and the substitution of the threads from one beam for those of the other beam when the first half of the rug had been completed in the loom.

Prior to this invention it has been practically impossible to print a single continuous warp thread of a length sufficient to provide in one continuous thread pile tufts for the whole of one 45 warpwise extending course thereof, as such, under the printing method of the prior art, would necessitate the use of such a large drum that it could not be economically manufactured and handled.

The principal object of the present invention 50 is to utilize a drum of the normal practical size and to arrange a continuous warp thread in such a manner on the periphery of the normally sized drum as to provide for a complete single course of pile tufts from end to end of a rug, or other fabric unit, of the larger size as above noted.

Another object of the invention is to lay the continuous warp thread on the face of the tap drum in a manner to provide, in the one length of thread, a plurality of rug lengths, said thread to be wound on a single beam in predetermined lateral relation to other threads of a similar character but different color distribution as required for each transversely extending course of pile tufts in the series of rugs.

5 Another object of the invention is to provide 10 means by which a plurality of threads will be laid simultaneously on the face of the tap drum in lateral spaced relation to each other, first in one direction circumferentially of the drum from one line or anchorage to a second line or anchorage, through an arc of approximately 350° and then in an opposite direction through said arc around the periphery of the drum to the first said anchorage whereby each thread so laid will be doubled and redoubled upon itself and thereby 15 receive and contain the various color units for 20 both halves of each of a plurality of rugs.

Another object of the invention is to provide 25 escapement means by which the thread-laying elements will be moved step by step laterally of the face of the drum, one step each time the rotation of the drum is reversed in laying the threads back and forth around the periphery of the drum, whereby the single layer lateral abutting 30 relation of the thread sections is obtained on the face of the drum.

Other objects of the invention and the construction and operation of the mechanism forming the subject matter of the present application will be fully disclosed hereinafter, reference being 35 had to the accompanying drawings; of which:

Figs. 1a and 1b constitute a front elevation of the drum as taken on the line 2—2, Fig. 1a.

Fig. 3 is an enlarged front elevation of the escapement mechanism shown in Fig. 1b;

Fig. 4 is an end elevation of the mechanism shown in Fig. 3;

Fig. 20 illustrates one continuous pile thread for making a single course of pile tufts longitudinally of the fabric unit such as on the line 19—19, Fig. 18;

30 Fig. 21 shows the thread of Fig. 20 doubled upon itself for simultaneous printing of the duplicate color units of the opposite halves of the pile tuft course represented by the thread shown in Fig. 20; and

35 Fig. 22 shows a single warp thread doubled and redoubled to produce a plurality of rug lengths in a single thread.

As shown in Figs. 1a, 1b and 2, the printing machine comprises a general framework indicated at 1 which is provided with bearings 2 for rotatably supporting a shaft 3.

Secured to the shaft 3 is a plurality of wheels 4 upon the rims 5 of which is secured a series of laterally abutting segmental staves 6 which constitute the thread-carrying face of the tap drum 10. The outer surface of the staves 6 are preferably covered by a sheet of rubber, oilcloth or other waterproof and readily washable material 7.

Interposed between the staves 6, 6 in spaced relation to each other, circumferentially of the tap drum 10, is a pair of anchor plates 8, 8 respectively, by which the opposite ends of the cover sheet 7 are secured in place and by which the said cover sheet is held in a taut state in snug fitting relation to the face of the drum as provided by the outer surface of the segmental staves 6, 6.

Each of the anchor plates 8 is provided with a cavity 9 in which the end of the sheet reposes and from which the said sheet extends between a clamp plate 11 secured to the anchor plate 8 and a pinch bar 13 which, as illustrated in Fig. 13, tapers lengthwise progressively from end to end thereof and which is adapted to be driven into a receiving slot 14 formed in the anchor plate 8. The recess 14 is provided at one side with an undercut edge 15 adapted to receive a beveled edge 16 of the tapered pinch bar 13. Longitudinal movement of the pinch bar 13 in one direction will effect lateral movement thereof toward the fixed bar 11, thereby clamping the end of the cover sheet 7 firmly therebetween.

Each of the fixed bars 11 is provided with a series of laterally spaced pins 20, 20 about which

the individual warp threads are adapted to be laid during oscillatory movements of the tap drum 10.

The laterally spaced pins 20, 20 on the bars 11, 11 respectively are divided into a plurality of groups a, a and b, b transversely of the drum 10. Each group a on one of the pin bars 11 is substantially in alignment, circumferentially of the drum, with a group b carried by the other of the bars 11. Each pair of circumferentially aligned groups a and b is adapted to be served with one single continuous yarn x delivered to the pins successively by a thread-laying unit 25 such as that illustrated in Fig. 8.

Each of the thread-laying units 25 comprises a substantially U-shaped bracket 26 composed of a base 27 which is provided with a groove 28 adapted to receive, and, for the purposes of adjustment, to slide on and longitudinally of a carrier bar 30. Each bracket 26 is adapted to be locked in adjusted position on the carrier bar 30 by a bolt 29 passing through a short slot formed in the bar and tapped into the base 27 of the bracket 26. Projecting vertically at each of the opposite ends of the base 27 is an upright 31 in 25 which is slidably mounted a rectangular stem 32. The stem 32 is slidably held in slots 33, 33 formed in the uprights 31, 31 respectively, by cap plates 34, 34.

Secured to the stem 32 intermediate the uprights 31, 31 is a collar 35 between one side of which and the inner face of one of the uprights 31 and encircling the stem 32 is a spring 36 tending to move the said stem longitudinally in a direction toward the face of the tap drum 10 at 35 all times.

Secured to the end of the stem 32 intermediate the bracket 26 and the periphery of the tap drum 10 is a thin plate-like head 49 which is provided with an eye 39 for the passage of the thread x, 40 and with a laterally extending lip 38 for purposes hereinafter described.

The tap drum 10 is adapted to oscillate about the axis of the shaft 3, first in one direction and then in an opposite direction through an arc of 45 substantially 350°, between which the thread-laying units 25 are adapted to be shifted laterally, or transversely of the drum 10, a distance equal to the spacing of the pins 20 thereon, whereby each of the said thread-laying units will carry the thread x respectively carried thereby around one of the pins 20, which, upon reverse movement of the drum 10, will catch the thread and hold it in position while another section of the thread is laid on the periphery of the drum in substantially parallel lateral abutting relation to the section previously laid thereon.

During each thread-laying operation the lip 38 rides under the last said section of the thread as illustrated in Fig. 7 and tends to straighten the 60 thread section on and circumferentially of the drum, in order that the new thread will be laid in snug-abutting relation to the previously laid thread and substantially parallel thereto, without overlapping.

65 Lateral shifting of the thread-laying units 25 is accomplished by the mechanism shown in Figs. 1b, 3, 4, 5 and 7. The bar 30 to which all the thread-laying units 25 are rigidly secured is provided with a rack bar 50 which is rigidly secured 70 thereto. The rack 50 is provided with a series of teeth 51 alternately with spaces 52 for receiving the lower ends 53 and 54 of escapement pawls 55 and 56 respectively.

The escapement pawls 55 and 56, in the present 75

instance, take the form of vertically movable plungers slidably mounted adjacent their lower ends in a bar 51 which is rigidly secured to a bracket 58 fastened to or forming part of the framework of the machine. Adjacent their upper ends, the plungers 55 and 56 are slidably mounted in a plate 59 which is also rigidly secured to the bracket 58 and provides a support for bearings 60 and 61. Pivotally mounted in the bearings 60 and 61 is a pair of shafts 62 and 63, provided with levers 64 and 65 respectively. The levers 64 and 65 are connected by links 66 and 67 to the upper ends of the escapement pawls 55 and 56 respectively.

Secured to each of the escapement pawls 55 and 56 is a collar 68 between which and the lower surface of the plate 59 is provided a spring 69 tending at all times to force the lower ends 53 and 54 of the escapement pawls 55 and 56 into engagement with the teeth 51 or into the spaces 52 of the rack bar 50.

The lateral spacing of the pawls 55 and 56 is such that at such time as one of said pawls is seated in one of the openings 52 of the rack bar 50 the other of the pawls is riding the top surface of one of the teeth 51 of the said rack bar, in order that, as the one pawl is raised out of the occupied space the other pawl is in a position to drop into one of the spaces in the rack bar, whereby the bar 30 will be moved laterally to the extent of substantially one-half of the spacing of the teeth 51 of the rack bar, which is equal to the spacing of the anchor pins 20, 20.

Movement of the bar 30 may be accomplished by any suitable mechanism which in the present instance comprises a flexible element 70 having one end secured to one end of the bar 30. The said flexible element 70 then passes around a horizontally mounted sheave 71 and is provided at its second end with a weight 72 tending at all times to move the bar 30 and the thread-laying units 25, 25 to the right as viewed in Figs. 1a, 1b and 3.

Alternate releasings of the pawls 55 and 56 is accomplished through the medium of arms 73 and 74 respectively secured to the shafts 62 and 63, said arms being arranged to be engaged by trip cams 75 and 76 mounted in circumferentially spaced relation to each other on the periphery of the tap drum 10, adjacent one edge thereof.

As the tap drum 10 rotates in one direction, for example in the direction of the arrow *y* Fig. 4, the cam 75 rides away from the arm 73 and permits the pawl 55 to come to rest on the top of one of the teeth 51 of the rack bar 50, it being noted that at such time the lower end 54 of the pawl 56 is disposed in one of the spaces 52 in the said rack bar. As the rotation of the drum 10 continues in the direction of the arrow *y*, through an arc of substantially 350°, the cam 76 near the end of such movement of the tap drum will engage the arm 74 and thereby raise the pawl 56 out of the space 52 in the rack bar 50, whereupon the bar 30 will move to the right, as viewed in Fig. 3, and the pawl 55 will drop into one of the spacers in the rack bar 50, thereby arresting the movement of the bar 30 by which the thread-laying units 25, 25 are moved laterally to the extent of the spacing between two of the pins 20, 20.

The movement of the tap drum 10 is then reversed, whereby the said drum moves in the direction of the arrow *z*, Fig. 4, through an arc of substantially 350°, as before noted, until the

cam 75 again contacts with the arm 73 which lifts the pawl 55 out of its occupied space while the pawl 56 is permitted to drop into the space next to the tooth upon which the lower end 54 of said pawl is riding.

In this manner the bar 30 and all of the thread-laying units 25 are moved step by step across the face of the tap drum between the oscillations of the tap drum, causing each of the threads *x* to be laid continuously back and forth around the periphery of the tap drum throughout the breadth of the face of the tap drum as defined by the pin groups *a*, *b*.

During such laying of the threads *x*, said threads are drawn from individual supply spools 80, 80 which are rotatably mounted on substantially horizontally extending spindles 81, 81 respectively, said spindles being supported in brackets 82, 82 respectively which are carried by transversely extending bars 83, 83 secured to the front frame 84 of the machine.

The threads *x*, *x* are maintained in a substantially taut condition by brake shoes 85, 85 bearing directly on the threads wound on the spools 80, 80, said brake shoes being secured to or forming part of brake arms 86, 86 respectively pivoted at 87 to brackets 88 which are secured to the transverse bars 83, 83. Each brake arm 86 is provided with a tension weight 89 which maintains frictional contact between the brake shoe 85 and the spool with which such brake shoe cooperates.

The threads *x* pass from the supply spools 80, 80 over a thread guide bar 90 supported by brackets 91, 91 which are secured to the front frame 84 of the machine.

Pivotedly mounted on the guide bar 91 is a series of drop fingers 92 having thread eyes 93 through which the threads *x*, *x* pass respectively and from which the said threads extend to thread eyes 94 respectively carried by the thread-laying units 25, thereby guiding the threads *x* to the laying heads 40, 40 of said units.

The front frame 84 is also provided with brackets 95, 95 which afford open topped slide bearings for the thread-laying bar 30 which is held down in said slide bearings by a spring 94. Anti-friction rollers 96 and 97 may be provided on one or both of the brackets 95 to prevent sticking of the bar in the guide bearings of the brackets 95 during the intermittent longitudinal movements of the bar. In the present instance the anti-friction bearings are shown as being used at one end only of the bar 30, as in Fig. 1a.

Oscillation of the drum 10 is accomplished through a series of internal gear teeth 100 carried by and disposed adjacent one end of the said drum and arranged to be engaged by the teeth of a pinion 101 which is freely rotatably mounted on a horizontal shaft 102. The shaft 102 is rotatably mounted in bearings 103, 103 which are secured to or form a part of a bracket 104 which is rigidly secured to the frame 1

The pinion 101 is secured to one end of a sleeve 105 which is freely mounted on the shaft 102, within the bearing 103, the opposite end of the said sleeve being provided with a clutch element 106 which is adapted to be engaged by a second clutch element 107 slidably mounted on and splined to the shaft 102.

The clutch element 107 is provided with a hub 108 circumferentially grooved at 109 to receive short pins 110 carried by the arms 111 of the

- forked end 112 formed on the clutch-control lever 113 which is pivotally mounted at 114 to the frame of the machine; said lever being provided with a handle 115 by which the said clutch element 107 may be actuated to connect or disconnect the clutch element 106 with the shaft 102, whereby the pinion 101 through the gear teeth 100 will effect rotation of the tap drum 10 about the axis of the shaft 3.
10. The shaft 102 is driven by a pulley 116 secured thereto and which is operatively connected by a belt 117 to a pulley 118 secured to one end of a shaft 119 which is rotatably mounted in a bearing 120 rigidly mounted on the frame 1. The opposite end of the shaft 119 is provided with a sprocket wheel 121 which, through a chain 122, is operatively connected to a corresponding sprocket on one end of the armature shaft of a reversible motor (not shown).
15. The reversible driving motor is adapted to drive the drum 10, through the chain of mechanism above described, first in one direction and then in an opposite direction, through the arc of substantially 350° as above noted, under control of mechanism carried by the drum 10.
20. Reversal of the motor is accomplished by means of a pair of cams 125 and 126 adjustably mounted on a supporting segmental bar 127 secured to one of the supporting wheels 4 of the tap drum 10. Each of the cams 125, 126 comprises a swell 128 forming the head of a C clamp having an opposing head 129 in which is mounted a clamp screw 130 by which the said cams 125 and 126 are respectively secured to the bar 127.
25. Mounted on the frame 1 in the circular path of the cams 125 and 126 is a switch box 131 which is provided with switch-actuating plungers 132 and 133, which are respectively engaged, alternately, at the opposite ends of the oscillations of the tap drum 10, by the cams 125 and 126 for effecting reversal of the driving motor above noted.
30. Electrically connected in circuit with the motor is a magnetic brake comprising a solenoid 135, the plunger 136 of which is connected by a link 137 with a brake-actuating arm 138. The actuating arm 138 is pivotally mounted at 139 on a brake lever 140 arranged at one side of the shaft 102 and provided with a brake shoe 141 for engagement with the peripheral surface of a brake drum 142 secured to the shaft 102. Opposing the brake shoe 141 and engaging the periphery of the drum 142 at the opposite side thereof is a second brake shoe 143 which is carried by a second brake arm 144. The brake arms 140 and 144 are pivotally secured at 145 and 146 respectively to a base plate 147 which is rigidly mounted on a bracket 148 secured to the stationary bracket 104. The brake-actuating arm 138 is provided with a right angle extension 149 which is pivotally connected at 150 to a block 151 secured to a brake rod 152, one end of which is anchored in a block 153 pivotally mounted at 154 to the brake arm 144. The opposite end of the brake rod 152 is slidably mounted in a plate 155 secured to the brake arm 140. Beyond the plate 155 the brake rod 152 is provided with a head or washer 156 between which and the plate 155 is disposed a spring 157, tending at all times to draw the free ends of the brake arms 140 and 144 toward each other to apply the brake shoes 141 and 143 to the drum 142, to stop the rotation of the shaft 102, when the circuit to the driving motor is interrupted by actuation of the switch-

actuating plungers 132 and 133 of the reversing switch 131 above referred to.

During energization of the motor the coil 135 is also energized which causes a downward movement of the plunger 136 by which the actuating arm 138 is rocked about its pivot 139 on the brake arm 140 to separate the brake arms 140 and 144 for releasing the brake shoes 141 and 143 from the brake drum 142 whereby the brake is released during the periods of movement of the drum 10 in either direction.

Stopping of the motor and the consequent stopping of the drum 10 or a reversal of the movement thereof may be accomplished at any time by operation of the control switch 160 provided with buttons 161, 162 and 163 which control switches which are connected in electric circuit forming no part of the present invention with the switches in the switch box 131 above referred to.

Stopping of the drum 10 at any time as a result of the breaking of one of the yarns *x* may be accomplished by the finger 92 associated with such thread dropping into contact with a contact bar 165 carried by and insulated from the brackets 91, 91 and connected to one side of a part of the electric circuit above noted, the opposite side of said part of the electrical circuit being formed by the framework of the machine or by the bar 90 upon which the drop fingers 92 are mounted.

After each of the threads *x* has been laid on the periphery of the tap drum 10 around the corresponding series of pins *a*, *b* the thread is severed from the supply coming from the spools 80 and secured in any suitable manner to the drum or to the last pin of the series, it being noted that the opposite end of each thread, at the beginning of the thread-laying operation, is likewise secured in any desired manner to the tap drum as by knotting about the first of the pins 20 of the series.

After the tap drum 10 has been completely loaded and the threads *x*, *x* severed from the supply in the manner above noted the clutch 106—107 is released permitting the drum 10 to be rotated freely about its axis for the purpose of bringing the various portions of the threads into alignment with the color-laying wheel 114 of the color unit 115 which, as above noted, comprises a carriage 116 mounted on rails 117 for movement transversely of or parallel to the axis of the tap drum 10 whereby the number of threads laid on the face of the tap drum will receive the various colors which go to make up one longitudinally disposed course of pile tufts in the finished carpet, it being noted that each adjacently disposed pair of threads or thread sections on the tap drum 10 are exact duplications of each other, whereby each thread section will produce the tufts for one-half the length of the carpet unit or rug to be produced and whereby the two adjacently disposed thread sections will complete the course of pile tufts throughout the full length of the unit of fabric in which the thread is incorporated.

Those portions of the thread which pass around the pins 20 as the coloring of the threads is completed and before the threads are removed from the tap drum are colored by hand with a color corresponding to that of the color unit which has been applied to the thread sections immediately adjacent the rows of pins 20, whereby continuity of the color is provided and no line of demarcation between the two halves of the thread going into any single longitudinal course of tufts is perceptible.

The movement of the drum 10 to bring the various portions of the threads carried thereby into printing alignment with the unit 175 is accomplished in the usual manner employed with 5 tap drums of the prior art and the mechanism by which such movements of the tap drum are accomplished, and whereby alignment of the various portions of the thread sections is assured has been eliminated from the drawings in the present 10 instance as the same form no part of the present invention.

Fig. 18 illustrates a fabric unit or rug A, which is divided longitudinally into sections or halves A¹ and A², respectively, while Fig. 19 shows a 15 single longitudinally or warpwise extending line or course of pile tufts or uncut loops A³, as the case may be, which are formed of the continuous thread x shown in Fig. 20, the two halves x¹ and x² of which are provided with a plurality of differently colored color units C and C¹ disposed in 20 symmetrically balanced relation to each other at opposite sides of the center point c which forms the turn in the thread where the thread is looped around one of the anchorage pins 20 in the drum.

Fig. 22 illustrates the continuous thread x laid back and forth to provide a plurality of alternating sections x¹—x² to provide a plurality of continuous full lengths x end to end in the single continuous warp thread.

30 I claim:

1. A warp printing method which consists in laying a continuous warp thread back and forth between relatively spaced anchorages directly from a thread supply package to provide a series 35 of substantially parallel runs, and coloring said runs substantially simultaneously in units of predetermined order progressing from one toward the other of said anchorages.

2. A warp printing method which consists in laying a continuous warp thread back and forth between relatively spaced anchorages directly from a thread supply package to provide a series 40 of substantially parallel runs, coloring said runs substantially simultaneously in units of predetermined order progressing from one toward the other of said anchorages, and coloring the run-connecting turns of the thread at the said one of said anchorages in accordance with the coloring of the color unit next adjacent said one anchorage.

50 3. A warp printing method which consists in drawing a continuous warp thread from a thread supply package and directly laying said thread back and forth over a supporting surface between relatively spaced anchorages as a single layer composed of a series of substantially parallel thread runs, and coloring said runs in units of predetermined order progressing from one toward the other of said anchorages by a color applicator 55 passed transversely across the series.

4. A warp printing method which consists in drawing a continuous warp thread from a thread supply package and directly laying said thread back and forth over a supporting surface between relatively spaced anchorages as a single layer composed of a series of substantially parallel thread runs, coloring said runs in units of predetermined order progressing from one toward the other of said anchorages by a color applicator 60 passed transversely across the series, and coloring the run-connecting turns of the thread at the said one of said anchorages in accordance with the coloring of the color unit immediately adjacent said one anchorage.

75 5. A warp printing machine comprising a drum,

a series of posts projecting from the peripheral surface of said drum in laterally spaced relation transversely of said surface, a second series of laterally spaced posts projecting from said surface in circumferentially spaced relation to the first said series, and means for laying a continuous warp thread around the peripheral surface of said drum between and around said circumferentially spaced posts alternately. 5

6. A warp printing machine comprising a drum, 10 a series of posts projecting from the peripheral surface of said drum in laterally spaced relation transversely of said surface, a second series of laterally spaced posts projecting from said surface in circumferentially spaced relation to the first said series, and means for laying a continuous warp thread around the peripheral surface of said drum between and around said circumferentially spaced posts alternately on successive 15 posts of each series. 20

7. A warp printing machine comprising a drum, a series of posts projecting from the peripheral surface of said drum in laterally spaced relation transversely of said surface, a second series of laterally spaced posts projecting from said surface in circumferentially spaced relation to the first said series, means for laying a continuous warp thread around the peripheral surface of said drum between and around said circumferentially spaced posts alternately, and means for 25 moving said thread-laying means step by step transversely of the drum for laying the thread around the posts of each series successively. 30

8. A warp printing machine comprising a drum, 35 a series of posts projecting from the peripheral surface of said drum in laterally spaced relation transversely of said surface, a second series of laterally spaced posts projecting from said surface in circumferentially spaced relation to the first said series, means for laying a continuous 40 warp thread around the peripheral surface of said drum between and around said circumferentially spaced posts alternately, means for moving said thread-laying means step by step transversely of the drum for laying the thread around the 45 posts of each series successively, and means for oscillating said drum between the said intermittent transverse movements of said thread-laying means. 50

9. A warp printing machine comprising a drum, 55 a series of posts projecting from the peripheral surface of said drum in laterally spaced relation transversely of said surface, a second series of laterally spaced posts projecting from said surface in circumferentially spaced relation to the first said series, means for laying a continuous warp thread around the peripheral surface of said drum between and around said circumferentially spaced posts alternately, means for moving said thread-laying means step by step transversely of the drum for laying the thread around the posts of each series successively, means for oscillating said drum between the said intermittent transverse movements of said thread-laying means, and means carried by said drum for 60 effecting said transverse movements of the thread-laying means at the end of each oscillatory movement of the drum. 65

10. A warp printing machine comprising a drum, 70 a series of posts projecting from the peripheral surface of said drum in laterally spaced relation transversely of said surface, a second series of laterally spaced posts projecting from said surface in circumferentially spaced relation to the first said series, means for laying a contin- 75

uous warp thread around the peripheral surface of said drum between and around said circumferentially spaced posts alternately, means for moving said thread-laying means step by step 5 transversely of the drum for laying the thread around the posts of each series successively, means for oscillating said drum between the said intermittent transverse movements of said thread-laying means, means carried by said drum 10 for effecting said transverse movements of the thread-laying means at the end of each oscillatory movement of the drum, and means carried by said drum for controlling the said oscillatory movements thereof in timed relation to 15 the transverse movements of said thread-laying means.

11. The combination of a tap drum, two circumferentially spaced series of laterally spaced thread-retaining elements on the periphery of 20 said drum, thread-laying means, means for oscillating said drum to bring said circumferentially spaced series of elements alternately in thread-receiving relation to said thread-laying means, and means for moving said thread-laying 25 means transversely of the drum between the individual oscillatory movements thereof, for laying said thread to the individual elements of each series successively.

12. The combination of a tap drum, two circumferentially spaced series of laterally spaced 30

thread-retaining elements on the periphery of said drum, thread-laying means, means for oscillating said drum to bring said circumferentially spaced series of elements alternately in thread-receiving relation to said thread-laying means, a toothed element operatively connected to said thread-laying means, means for moving said toothed element and said thread-laying means in one direction, a pair of pawls operatively associated with said toothed element for arresting said movement, and means carried by said drum for alternately releasing said pawls from 10 said toothed element to permit intermittent movement of said thread-laying means transversely of the drum for laying said thread to the individual retaining elements of each series successively. 15

13. The combination of a tap drum, two circumferentially spaced series of laterally spaced thread-retaining elements on the periphery of 20 said drum, thread-laying means, means for oscillating said drum to bring said circumferentially spaced series of elements alternately in thread-receiving relation to said thread-laying means, and means for straightening the immediately precedingly laid section of the thread on the periphery of the drum to permit laying of the new thread section immediately adjacent thereto 25 during each oscillatory movement of the drum.
